CONNECTOR FOR ELECTRIC RECEPTACLES

Karl Hoehn, Canton, Ohio

Application October 21, 1946, Serial No. 704,687

3 Claims. (Cl. 285—6.5)

1

The invention relates to connectors for anchoring electrical cables or insulated conductors to electrical receptacles, such as outlet boxes.

A prior conventional type of connector embodies a split clamp for securing the cable at the outside of the box and a tubular exteriorly threaded stud extending through a knock-out hole of the outlet box, there being a separate screw provided for drawing the split clamp parts together and a nut for screwing on the stud inside the box to hold the connector in place. When such connectors are made from malleable castings, they are difficult to cast uniformly without defects which render them unsatisfactory.

On the other hand, when such connectors are formed from sheet metal, their manufacture is relatively complicated and expensive because the tubular stud must be formed from a flat blank and then swaged and threaded by additional operations, and the split clamp must be perforated and tapped.

Regardless of how such conventional connectors are made, each connector consists of at least three loose parts which require assembly on the job, and after the stud is inserted through a knock-out hole in the outlet box and the cable secured in the stud by the split clamp, the nut must be slipped over the end of the cable screwed on the inner threaded part of the stud while it projects into the box. Obviously, this is a difficult operation because it is awkward to reach into the cramped space within the box and start the nut on the threads of the stud with the fingers. Moreover, when the time required for this operation is multiplied by the large number of outlet boxes used in building construction, the added labor cost becomes a substantial item.

It is therefore an object of the present invention to provide a novel connector for an electrical receptacle, which connector overcomes the disadvantages of prior constructions and is simple and inexpensive to manufacture.

Another object is to provide a novel connector which has no loose parts requiring assembly on the job and apt to become lost or misplaced.

Another object is to provide a novel connector which is made entirely of sheet metal without requiring any additional tapping, swaging or threading operations.

Another object is to provide a novel connector which is adapted to be quickly and instantaneously secured in the box without screwing.

A further object is to provide a novel connector in which the electrical cable is secured in posi-

2

tion by a gravity latch, without requiring reaching into the box.

A still further object is to provide a novel connector which is quickly secured in an outlet box for securing an electrical cable, and which is adapted to quickly release the cable and be easily removed from the box.

Finally, it is an object of the present invention to provide a novel and improved connector which is inexpensively manufactured from a minimum amount of sheet metal and which is quickly and easily installed on the job without requiring any tools.

These and other objects are accomplished by the parts, elements, constructions, arrangements and combinations which comprise the present invention, the nature of which is set forth in the following general statement, a preferred embodiment of which is set forth in the following description and illustrated in the accompanying drawings, and which is particularly and distinctly pointed out and set forth in the appended claims forming part hereof.

In general terms, the invention may be stated as including a generally tubular sheet metal body having a slotted top with spaced upright ears at one end and the other end being adapted for insertion through a knock-out hole of an outlet box, and a latch pivoted in the ears for swinging through the slot into the body, said latch having an upwardly curved leg for engaging under an upper edge of the knock-out hole and a downwardly curved leg for engaging a cable passing through the connector body into the box.

Referring to the drawing forming part hereof in which a preferred embodiment of the invention is shown by way of example;

Fig. 1 is an enlarged detached isometric view of the improved connector, with a portion of one ear broken away to show the manner of pivoting the latch therein;

Fig. 2 is a transverse sectional view through an outlet box showing the novel connector being inserted in one of the knock-out holes thereof;

Fig. 3 is a similar view showing the novel connector in position for securing a cable passing into the box;

Fig. 4 is a similar view showing the manner of removing the cable from the connector; and

Fig. 5 is a detached isometric view of a shim for facilitating removal of the cable from the connector.

Similar numerals refer to similar parts throughout the several views of the drawing.

The outlet box shown in the drawing is of usual

construction and preferably includes a perforated bottom wall 6 with side walls 7 and 8 extending at right angles to the bottom wall. The side walls 7 and 8 are provided with the usual knock-out disks 9 for forming when removed preferably circular knock-out holes 10 in opposite side walls of the box, and electrical cables or conduits are led into the box through the knock-out holes 10.

The outlet box is preferably provided with attaching means which may be attaching flanges 11 preferably located in diagonally opposite corners, one of said flanges being shown in the drawing, and an attaching screw 12 being threaded in each flange 11. The construction of the outlet box is well known, and is shown merely by way of example as being one form of outlet box to which the novel connector may be applied.

The connector preferably includes a tubular body 13 which is formed in a substantially cylindrical shape to fit rather closely within the circular knock-out holes 10 of the outlet box. Preferably, the connector is formed from a flat blank of sheet metal which may be stamped out, and the upper edges 14 of the formed body are spaced apart to form a slot 15 extending longitudinally thereof. At one end of the slot a pair of ears 16 project upwardly therefrom, and the ears 16 are adapted to be positioned exteriorly of the outlet box when the other end of the body is inserted through one of the holes 10 thereof. Obviously, the body 13 of the connector may be made in any shape as required to fit into a knock-out hole which is not circular in shape.

The latch for securing the body member 13 in a knock-out hole 10 is preferably also formed of a piece of sheet metal, and is adapted for swinging through the slot 15 within the body member 13. The latch preferably includes an upper folded edge portion 17 having outwardly projecting tongues 18 which are rotatably or pivotally mounted in holes 19 in the ears 16. Preferably, body member 13 is sufficiently resilient that the ears 16 can be sprung apart to allow insertion of the tongues 18 into the holes 19 from the insides of the ears, thus positioning the latch between the ears with the tongues pivoted in the holes 19 thereof.

As shown, the latch includes an upper leg 20 which is preferably of U-shape and curves downwardly from edge portion 17 and then upwardly to provide an upper flange portion 21 adapted to take under and engage behind the upper edge of the knock-out hole 10 in which the body member is inserted. Thus, the leg 20 provides for frictionally clamping the connector to the outlet box when the flange 21 is forced upwardly through the hole 10 and behind the upper edge thereof.

The latch is also provided with a lower leg 22 extending downwardly from edge 17 and having a downwardly curved portion 23 for extending into the opposite end of the body portion 13 and terminating in a beveled edge 24. The edge 24 is adapted for engaging and digging into the surface of an electrical cable 25 passing through the body member 13 of the connector, as best shown in Fig. 3. As indicated in Figs. 2 and 3, the latch tends to swing downwardly by gravity, so that the beveled edge 24 of its lower leg is normally in a depending position.

In order to securely hold the connector in position within one of the knock-out holes 10 of an outlet box in the position of Fig. 3, means is preferably provided for fitting around the lower edge of the hole opposite to the upper leg 20 of

the latch. Such means may include a pair of spaced exterior projections 26 formed in the body member 13 in the side opposite the slot 15 by making indentations 27 on the interior surface thereof.

When the connector is inserted in one of the knock-out holes 10, it is tilted somewhat as indicated in Fig. 2, so that the bottom edge of the hole is positioned between the projections 26 before the front upper edge of the body member is inserted through the hole. After inserting the body member, the latch can be pressed inwardly from the outside to force the upper leg 20 upwardly against the top edge of the hole until the edge is frictionally clamped by the flange 21 of the upper leg, in the position shown in Fig. 3. Thereafter, the end of the cable 25 may be pushed into the box through the body member 13, and the beveled edge 24 will slide or scrape over the upper surface of the cable covering as the cable is pushed inwardly. A slight pull on the outer portion of the cable will then force the beveled edge downwardly into the cable surface so as to securely hold the same, and the harder the cable is pulled the more the beveled edge 24 will dig into the surface thereof.

Accordingly, when it is desired to insert the end of the cable 25 into the outlet box and secure the cable in position, the operation is speedily performed without any tools, merely by inserting the novel connector in the required knock-out hole and then inserting the end of the cable through the connector. Thus, the cable is secured without requiring screwing on a nut on the inside of the box or tightening a clamping screw.

If it is desired to remove the cable from the box, the same is accomplished by inserting a thin shim 28 of sheet metal into the box from the outside and between the beveled edge 24 of the latch and the cable 25, in the manner shown in Fig. 4. By then grasping the shim and cable, both the shim and cable can simultaneously be removed because the beveled edge 24 will easily slide over the smooth surface of the shim 28.

The novel connector is inexpensively made entirely of sheet metal without requiring any tapped holes or screw threads, is quickly and easily installed in an outlet box without requiring any tools, and has no loose parts such as screws or nuts which are apt to become lost.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical equivalents thereof obvious to those skilled in the art, are set forth in the appended claims.

I claim:

1. A cable connector for an electric outlet box including a substantially cylindrical body adapted at one end for projecting through a knock-out hole of the box, spaced upright ears on the other

end of said body, and a gravity latch pivoted on said ears for swinging within said body, said latch having an upwardly curved leg for frictionally clamping the upper edge of said hole, and a downwardly curved leg for engaging a cable passing through said body.

2. A cable connector for an electric outlet box including a tubular body adapted at one end for projecting through a knock-out hole of the box, a latch pivoted in the other end of said body, said latch having a leg for frictionally clamping behind an edge of said hole, and said latch having another leg for engaging a cable passing through said body, whereby the cable can be forced into the box past the latch but the lower latch leg normally prevents withdrawal of said cable.

3. A cable connector for an electric outlet box including a tubular body adapted at one end for projecting through a knock-out hole of the box,

a latch pivoted in the other end of said body, spaced projections on the body opposite said latch for fitting around one edge of said hole, said latch having a leg for frictionally clamping the opposite edge of said hole, and said latch having another leg for engaging a cable passing through said body, whereby a cable can be forced into the box past the latch but the engagement of the lower latch leg with the cable normally prevents withdrawal thereof.
